UNITED STATES PATENT OFFICE.

ORA B. GILBERT, OF DETROIT, MICHIGAN.

WINDOW-SHADE-HOLDING DEVICE.

Application filed May 15, 1924. Serial No. 713,612.

To all whom it may concern:

Be it known that I, ORA B. GILBERT, a citizen of the United States of America, residing in the city of Detroit, county of Wayne, State of Michigan, have invented certain new and useful Improvements in a Window-Shade-Holding Device, and declare the following to be a full, clear, and exact description of the same, such as will enable others skilled in the art to which it pertains to make and use the same, reference being had to the accompanying drawings and the marks thereon, and which form a part of this specification.

15 The object of my invention is to provide a shade holding device that can be effectively operated in combination with the adjustable window shade holder now in common use, yet to be concealed from view 20 within the room.

Another object is to provide a shade holding device that can be readily installed within the top window pocket of the ordinary window casing, and so designed and 25 arranged as to be adapted to supporting and operating the adjustable shade holder and at the same time conceal the supporting and operating device.

30 A further object is to produce a shade holding device that will at all times retain the adjustable shade holder supported therein, in a horizontal position across the window sash.

35 A still further object is to produce a shade holding device that is simple in construction, easily and efficiently operated and can be manufactured at a low cost.

These several objects are attained under the preferred construction and arrangement 40 of parts more fully hereinafter set forth.

Similar parts on all drawings are marked by similar numerals.

Fig. 1, is a front view of my invention as installed in the top window pocket, and applied to the adjustable window shade holder supported below.

Fig. 2 is a side view of the window frame showing the relative position of the device to the supporting frame.

50 Fig. 3 is an enlarged detail of the operating mechanism and supports for attaching same to the window pocket walls.

Fig. 4, is an end view of the detail shown in Fig. 3.

55 Fig. 5, is a detail of a modified form of the operating roller installed within the top

window pocket, having an extended end on the roller to receive an operating cord thereon.

Fig. 6, is an end view of the roller showing the operating cord attached.

Fig. 7, shows the device installed within the window casing, and having the operating cord at the side.

Fig. 8, is a side view of Fig. 7.

Fig. 9, is a detail of the rope guide used on the operating roller to keep the draw cord in place.

Fig. 10, is an end view of the rope guide.

Fig. 11, is a detail of the roller bearing, 70 as used within the window pocket for mounting the operating roller.

I will now describe more fully the detailed construction of my window shade holding device, referring to the drawings 75 and the marks thereon.

The general construction of my device consists of an elongated roller installed in the top window pocket of the window casing, and extending the entire width of the 80 window opening. The roller being so positioned that the front edge thereof lies near the inside face of the window casing cap, and is supported by bearings at either end thereof. Attached to each end of the roller are suspension ropes which are coiled 85

around the roller, and extend through openings in the top of the window casing, attaching to the ends of an adjustable shade holder, holding same suspended in the window opening. The roller as installed in the top window pocket, is provided with means for operating same by rotating same on the roller bearings, thus providing means for raising and lowering the adjustable 90 shade holder to any desired position in the window.

At the present time it is difficult to secure proper ventilation through the opening of the upper sash of a window, due to the presence of the ordinary window 100 shade mounted in the casing at the top, and which obstructs the free passage of air therethrough.

My device is used in combination with an adjustable curtain holder as set forth in a former Patent No. 1,158,677, 105 Nov. 2, 1915, and is a special means for suspending same in the window opening, and provided for a stable, rigid adjustable support for the shade holder, allowing said holder to be placed at any desired position in the window before drawing the shade mounted therein, and providing a clear, un-

obstructed opening at the top of the window for ventilation and light.

The roller —1— may be made of any suitable material, as wood or sheet metal, and extends across the entire width of the window opening. Both ends of the roller are provided with pintles —2— and —3—, which are mounted in the support brackets —4— and —5—. The brackets —4— and —5— are securely attached to the inner face of the window casing cap —6—. Inside the roller —1—, at one end thereof, is an operating spring —7—, having its inner end attached to the retaining roller —1—, and the outer end of said coil spring being attached to the pindle —3— loosely mounted in the end of the roller. The pivot —3— is engaged in a slot in the bracket bearing —5— preventing any rotation of the pivot, and is engaged to the roller only through the ratchet hooks —8— attached thereto. The pindle —2— is free to rotate in the bracket bearing —4—. The roll construction is similar to the construction of the ordinary spring window shade roller. Small adjustable cord supports —9— and —10— are attached to the ends of the roller —1— at the points —11—, said cords being coiled around the roller drum with a sufficient number of turns to allow for the length of adjustment desired for the supported window shade holder. The cord coils being wound on the roller in such a manner that the free ends pass from the roller over the front side thereof, and near the inner face of the window casing cap. The lower ends of the cord supports are attached to the ends of a window shade holder —12— by a knot in the end of the ropes. A wire frame —20— is adjusted on the roller —1— so as to partially inclose the coiled section of the support cords, for preventing them from loosening or sliding out of place, should the shade holder be raised and removed the weight from the cords. Inside the shade roller holder —12— is mounted the ordinary window shade roller —13—, of the spring roller type. This patent does not lay claim to the shade holder —12— or the inclosed window shade —13—, but is confined to the operating device for supporting and operating the shade holder. The shade roller —13— is also provided with an internal coil spring —14^a—, said roller being so designed that the said coil spring will operate the roller —12— and cause it to wind up when released by pulling on the attached shade —14—. It is essential to the operating of my device that the coil spring —7— in the roller —1— be somewhat stronger than the coil spring —14^a— in the shade roller —13—, thus preventing the holding device from operating when it is desired only to operate the shade within the shade holder. The curtain holder —12— is provided with a draw cord —15— attached to the end of the holder, shown in Fig. 1, or the cord may be attached to the center of the holder as illustrated in the Fig. 3. The position of the draw cord makes no difference to the invention and is only a matter of choice. In operating my device by pulling on the cord —15—, the adjustable shade holder may be raised or lowered as desired, by reason to the action of the coil spring —7— and connecting ratchets —8— in roller —1—, which is concealed in the top window pocket of the window casing, and may raise the shade holder to the top of the window and retain it firmly against the window casing cap, giving the window the appearance of permanently attached window shade. One of the important features about my device is that it is completely concealed within the top window pocket, and also provides a means for lowering the window shade for the purpose of an unobstructed passage for ventilation and for light, yet retaining the full use of the window shade.

A modified form of my shade holding device is shown in Figs. 5, 6, 7, and 8. The principle involved is exactly the same as already set forth in the roller described, and the mechanical detail is varied only in the end of the roller —19— by omitting the internal coil spring —7— shown in Fig. 3. The roller —19— is operated by means of the pull cord —16—, which is coiled about the end of the roller so as to unwind as the support cords —9— and —10— are wound thereon. The weight of the curtain holder —12— is sufficient to unwind the roller —19— when released by the pull cord —16—, thus lowering the shade holder —12— to any desired position. Same is also raised as desired by pulling on the cord —16—, thus rewinding the support cords on the roller —19—. The cord —16— is passed through a cam pinch pulley —17— fastened to the outside of the window casing, and which is provided with a self locking device for holding the cord —16— in any position desired. The shade is adjusted in the same manner as described in the preferred form heretofore set forth. Over the coiled section of the ropes —10— and —16—, is also a wire frame —18—, inclosing the pull cord with one of the support cords, and prevents same from loosening and uncoiling should the weight of the shade holder be removed. The center ring —a—, of the wire frame —18—, is of a size to allow the roller body —19— to rotate freely therein, while the end rings —b— are slightly enlarged to slide freely over the coils of the rope, or cord as wound on the roller —19—. The wire frame is prevented from rotating by the extension of the cords leading from the roller, but the

250

1,550,899

said roller and coils move freely therein as the device is in operation. The center ring —a— being placed on the roller so as to come between the support cord —10— and the pull cord —16—. It will be seen that as one cord unwinds, the other cord winds up on the roller, causing the frame —18— to move slightly along the body of the roller, and always in a position to prevent any loosening of the coils should the cord be slackened.

Having fully described my shade holding device, what I claim as my invention and desire to secure by Letters Patent, is:

15   Claims:

1. A shade holding device adapted for installation within the top window pocket of a window casing for supporting and adjusting a window shade holder within the window opening, comprising a horizontally mounted roller extending the full width of the window pocket, bearing brackets at each end of the said roller for mounting same therein, a support rope attached to each end of the said roller, said ropes being coiled around the ends of the roller and suspended through openings in the top of the window casing directly into the window opening means for holding said coiled rope tight on the roller, means for attaching the ends of said support ropes to the ends of an adjust-

able

able) window shade holder, and means for rotating said roller on its support bearings for winding said support ropes thereon.

2. A mechanical shade holding device 35 adapted for installation in the top window pocket of a window casing for supporting and adjusting a window shade holder within the window opening, comprising a horizontally mounted roller extending across the entire width of the top window pocket, pintles in the ends of the said roller, bearings attached to the inner face of the casing pocket for receiving and supporting said roller end pivots which are free to rotate therein, support ropes attached to each end of said horizontally mounted roller and coiled therearound, said support ropes being suspended through port openings in the top of the window casing directly into the open window and attached to ends of a window shade holder, a pull rope attached to the end of said roller and coiled therearound in the opposite direction to the support ropes, said pull rope being passed through a self locking support 50 pulley attached to the inner face of the window casing to regulate the rotation of the mounted roller, and means for holding the coiled rope tight on the roller.

In witness whereon I sign these specifications.

ORA B. GILBERT.
